WILLIAM H. NICHOLLS, OF OLD WESTBURY, AND ARTHUR D. ZIEBARTH, OF KEW GARDENS, NEW YORK, ASSIGNEES, BY DIRECT AND MESNE ASSIGNMENTS, TO WM. H. NICHOLLS CO. INC., OF RICHMOND HILL, NEW YORK, A CORPORATION OF NEW YORK

MOLDING MACHINE

Application filed November 19, 1930. Serial No. 496,670.

Important objects of the present invention are, to provide a roll-over molding machine of generally improved design; to provide such a machine which will be efficient and easy to operate; to provide a roll-over molding machine wherein jolting mechanism, mold-squeezing mechanism and pattern-drawing mechanism are all embodied in a roll-over unit mounted for rotation about a lateral axis; to mount said unit so that it will be substantially balanced about its axis of rotation and will roll over easily; to provide satisfactory means for operating the jolt; squeeze and draw mechanisms of said rotatable means by fluid pressure; to provide simple and satisfactory fluid pressure operated means for performing the roll-over operation; to provide means designed to facilitate the control of the fluid pressure operated means; to provide an improved roll-over molding machine of the trunnion type; to provide a roll-over molding machine wherein a flask and pattern support and a squeeze head are joined together and supported in a unit by fluid pressure operated mechanism for squeezing and pattern drawing and wherein said mechanism in turn has a lateral trunnion which is mounted to rotatably support the unit; to provide in a molding machine improved fluid pressure operated means for mold squeezing and pattern drawing; and to provide other improved features which will appear hereinafter.

In the drawings, Fig. 1 is a plan view of the molding machine;

Fig. 2 a vertical section taken on the line 2—2 of Fig. 1;

Fig. 3 a side view of the machine upon a smaller scale showing the squeezing operation;

Fig. 4 a fragmentary sectional view of the machine showing the pattern-drawing operation;

Fig. 5 an elevation of the machine looking toward the opposite side thereof;

Fig. 6 a section taken on the line 6—6 of Fig. 2;

Fig. 7 a detail section taken on the line 7—7 of Fig. 2;

Fig. 8 a front elevation of a portion of the machine;

Fig. 9 a sectional view of the roll-over control valve;

Fig. 10 a section taken on the line 10—10 of Fig. 9; and

Fig. 11 a sectional view of one of the check valves of the roll-over control pipes.

The molding machine comprises broadly, a pedestal 1 and a mold-forming roll-over unit 2. Said unit is mounted upon the pedestal for substantially balanced rotation about a lateral axis and includes all of the mechanism required for jolting, mold squeezing and pattern drawing. These operations are performed by means of fluid pressure, and fluid pressure is also employed for rotating the unit.

The pedestal 1 comprises a hollow casting formed with a broad base 3 which, in the present instance, is bolted as at 4 to a foundation 5. At its upper end the pedestal casting is formed with a long, horizontal bearing-box 6 which tapers toward one end, is formed within its larger end with a cylindrical bearing surface 7 and within its smaller end with a materially smaller cylindrical bearing surface 8. Within the hollow upright portion of the pedestal is mounted a fluid pressure operated mechanism for effecting the roll-over, as will be described hereinafter.

The mold-forming unit 2 includes a casting forming a rather long cylinder 9 which is normally upright and has a closed lower end 10 and an open upper end. At a point near the upper end the casting is integrally formed with a long, hollow, laterally extending trunnion 11 which extends through the bearing box 6 and is correspondingly tapered. Cylindrical bearing surfaces 12 and 13 formed upon the trunnion oppose the bearing surfaces 7 and 8 respectively of the bearing box, and anti-friction rollers 14 are interposed between said opposed bearing surfaces. The rollers are confined endwise by ribs 15 formed upon the trunnion, by a plate 16 bolted to the free end of the trunnion and by a flat surface 17 formed upon the cylinder 9, around the root of the trunnion. The plate 16 abuts the outer end of the bearing box to prevent withdrawal

of the trunnion, and a circular rib 18 formed upon the cylinder 9 fits around the opposite end of the bearing box. At its free end the trunnion is formed with a reduced nipple-like 5 extension 19 having a bore opening into the interior of the hollow trunnion and forming part of a fluid pressure supply connection for the mechanisms of the roll-over unit.

Near its lower end the cylinder casting 9 is 10 integrally formed with a lateral extension projecting in an opposite direction from the trunnion and defining a smaller cylinder 20 extending parallel to cylinder 9, and an oil chamber 21 between said cylinders. Cylinder 20 is closed at its lower end and open at 15 its upper end and forms part of a jolt mechanism. A hollow jolt piston 22 is fitted to reciprocate in the cylinder and has a flat table 23 cast upon its upper end and normally resting upon a flat surface 24 surrounding the open end of the cylinder. Said table forms 20 a support for a mold flask and a carrier for a mold pattern. For the admission of fluid pressure to the jolt cylinder for the jolting operation said cylinder is formed with an 25 admission port 25 upon its outer or forward side, spaced upward from the lower end of the jolt piston in the normal position of the latter. Port 25 opens into an annular groove 30 26 formed in the piston, and said groove communicates through apertures 27 with a cavity 28 formed in the lower end of the piston. Below the port 25 the cylinder is formed with an exhaust port 29 normally closed by the 35 piston.

Fluid under pressure is supplied to admission port 25 through a valve 30 mounted upon the cylinder. Said valve is normally closed by the fluid pressure assisted by spring pressure if required and has a forwardly extending stem 31 for opening it. A lever 32 is pivoted as at 33 to the casing of the valve and has a depending arm engageable with the valve stem for pushing it inward and adapted to be 40 pressed by the knee of the operator. A tension spring 34 is anchored to the upper end of the lever and to the cylinder and normally holds the lever rocked away from the valve stem. Lever 32 also serves for the retraction 45 of a lock which is provided to hold the jolt piston in place when rolled over. Said lock comprises a bolt 35 slidable in a bore formed in the front of the cylinder and having a tapered inner end engageable in a tapered 50 keeper aperture formed in a bushing 36 mounted in the piston. At its outer end the bolt has a pin and slot operative connection 55 with the lever at a point between the pivot of the lever and the spring connection, so that 60 the spring normally holds the bolt engaged in the keeper aperture. When the lever is rocked, however for opening the valve 30 the bolt is also retracted to permit jolting movement of the piston. Preferably there is sufficient clearance between the lever and the

valve stem to permit retraction of the bolt before the stem is engaged.

The jolt piston is prevented from turning, and from moving too far outward under some circumstances by a bolt 38 screwed into the 70 table 23, slidably fitted in a boss formed in the top wall of the oil chamber and extending down into said chamber where it is provided with a stop nut 39 engageable with said boss. Directly beneath the bolt the lower 75 wall of the oil chamber is formed with an aperture giving access to the nut and normally closed by a threaded lug 40. Similarly the lower end of the jolt cylinder has an aperture normally closed by a threaded plug 80 41. Within the oil chamber is an oblique fin 42 which combines with the walls to form a trough, when in rolled over position, and one or more oil ports 43 lead from said trough to the interior of the jolt cylinder for lubricating it. An oil pipe 43' leads from the oil chamber to the interior of the cylinder 9.

Slidably fitted in the large cylinder 9 is a long, hollow, cylindrical plunger 44 which forms a shiftable support for a squeeze head 45. The upper end of the plunger is closed by a head 46 bolted thereto as at 47 and its lower end is closed by a piston-like head 48 fitted in the plunger and secured to it by screws 49. At a medial point in the length 90 of the plunger a piston-like partition disk 50 is fitted in the plunger and secured by screws 51. A stem 52 extends through the plunger along the axis thereof. At its lower end said stem is fixed to the closed end of 100 cylinder 9. The cylinder end has an aperture which is covered by a plate 53 removably held in place by bolts 54 and in turn formed with an aperture through which the lower end of the stem is passed. The stem is threaded at this point and two nuts 55 are screwed upon it and tightened against opposite sides of the plate. The upper end of the stem terminates at a point spaced below the plunger head 46 and has a piston 56 fixed to it and having a sliding fit in the plunger. Said piston has an aperture through which the end of the stem is passed and the stem is threaded and has two nuts 57 and 58 screwed upon it and tightened against opposite faces of the 110 piston. At a point between the lower plunger head and the partition disk or piston 50, and preferably nearer the latter, another piston 59 is fixed to the stem and has a sliding fit in the plunger, the stem being passed through 120 an aperture in the piston, threaded and having two nuts 59' screwed upon it and tightened against the opposite faces of the piston.

Pistons 56 and 59 have packing engaging the plunger, and the plunger pistons 48 and 50 have packing engaging the stem, to prevent leakage. The interior of the plunger is divided by the various pistons into three fluid expansion chambers 60, 61 and 62. Chamber 60 is located between the upper plunger head 130

46 and the stem piston 56, chamber 61 between piston 56 and the plunger piston 50, and chamber 62 between the plunger piston 59 and the lower plunger head or piston 48. The 5 stem has a fluid passage 63 extending the length thereof, and lateral ports 64 and 65 through which said passage communicates with the chambers 61 and 62 respectively. The upper end of passage 63 is closed by a 10 plug and its lower end has a fluid supply and exhaust connection. A port 66 leads through the plunger head 47 into the chamber 60 and also has a fluid supply and exhaust connection.

15 Admission of sufficient fluid pressure to chamber 60 will cause the plunger to move upward with reference to Fig. 2, since the plunger is movable in cylinder 9 while the piston 56 is fixed. Thereby the squeeze head 20 45 is moved farther away from the flask support 23. This movement is automatically limited by a locking means comprising a hook 67 which is pivoted, as at 68, to the under side of the plunger head 47 and is adapted to 25 gravitate into engagement with a loop 69 formed upon the nut 57, and anchor thereto. Admission of fluid pressure to the chambers 61 and 62 through the stem passage 63 and ports 64 and 65 acts upon the plunger pistons 30 48 and 50 to force the plunger downward. Thereby the squeeze head is moved toward the flask support for mold-squeezing and for holding the flask in place during the roll-over operation.

35 The mounting for the squeeze head 45 includes a lateral arm 70. An ear 71 is formed upon the plunger near the upper end thereof and the arm 70 is formed with a forked end which straddles said ear and is pivoted thereto upon a pin 72 for lateral swinging of the squeeze head into and out of register with the flask support. The squeeze head is provided with an upwardly extending central shank 73 which screws upward through a threaded bore in the free end of the arm and supports the squeeze head for vertical adjustment. A hand grip 74 is formed upon the free end of the arm for swinging it, and the pivoted end of the arm is formed with a 45 stop lug 75 engageable with the plunger to limit the swing of the arm which brings the squeeze head into register with the flask support.

50 Within the hollow pedestal 1 is a mechanism for effecting the roll-over of the mold-forming unit upon the trunnion 11. This mechanism includes a shaft 76 mounted in bearings 77 near the base of the pedestal. A sprocket wheel 78 is fixed to said shaft, another sprocket wheel 79 is fixed to the trunnion and a drive chain 80 is trained over said wheels. An adjustable device 81 is provided for tensioning the chain. Between the trunnion and shaft 76 extends a cylinder 82. Said cylinder has a closed upper end 55 formed with an ear 83 which is pivoted upon a pin 84 fixed within the pedestal. A piston 85 is fitted in the cylinder and has a piston rod 86 extending downward through a removable head 87 closing the lower end of the cylinder. At its lower end the piston rod is operatively connected to a crank 88 fixed to shaft 76. The cylinder has fluid admission and exhaust connections at its opposite ends for reciprocating the piston. A valve 89 is provided for controlling the fluid pressure in the cylinder.

60 Valve 89 comprises a body or base 90 and a cap 91 defining a chamber 92 and bolted to each other and to a plate 93. The latter covers an opening in the side of the pedestal nearest the roll-over unit and is bolted to the pedestal. A valve seat 94 is formed upon the valve body within the chamber 92, and a disk valve 95 is rotatably mounted upon said seat and is formed with two ports 96 and 97 spaced around its axis, and with a radial cavity 98 opening inward toward the valve seat. A stem 99 for rotating the valve is 65 rotatably fitted in a bore formed in the valve body and is fixed to the valve. An axial passage 100 formed in said stem communicates with the valve cavity 98 and places the latter in communication with a lateral exhaust port 101 formed in the valve body. The stem extends outward through an opening in the valve-supporting plate 93 and is provided with an operating handle 102 forming two oppositely extending arms having eyes at their extremities. The valve seat is formed 70 with two ports 103 and 104 spaced around the valve axis a less degree than the valve ports 96 and 97. A flexible tube or hose 105 connects port 103 to the upper end of the cylinder 82 and a flexible tube or hose 106 connects port 104 to the lower end of the cylinder. Connected to the valve cap 91 is a fluid supply pipe 107 opening into the valve chamber 92. A spring 108 interposed between the cap and the valve assists the fluid pressure to hold the valve upon its seat. Each of the tubes 105 and 106, adjacent its connection with the cylinder, is provided with a check valve 109 opening toward the cylinder but 75 provided with a bleed port 110 permitting exhaust of the fluid back to the tube.

80 When the handle 102 is rocked in one direction valve port 96 is brought into register with port 103 for supplying fluid pressure to the upper end of cylinder 82 and the valve cavity 98 is registered with port 104 for the exhaust of the cylinder below the piston 85. Thereby the piston is forced downward to cause rotation of the roll-over unit to rolled over position through the operative connection between the piston and the trunnion 11. When the handle is rocked in the opposite direction valve port 97 is registered with port 104 and valve cavity 98 is registered with port 103 for admission of fluid pressure to the 85 cylinder.

- lower end of cylinder 82 and exhaust of pressure from the upper end of the cylinder. Thereby the piston is forced upward to roll back the roll-over unit to normal position.
- 5 Movement of the valve disk to either of said positions is limited by engagement of a stop pin 111 with the ends of a slot 112 formed in the disk. The roll-over movement of the unit is limited by contact of a stop 113 formed upon the plunger 44 with one side of an elongated stop rib 114 formed upon the pedestal. Roll back movement of the unit is limited by contact of a stop 115 formed upon cylinder 9 with the opposite side of the rib 114.
- 10 Means are provided for convenient operation of the valve 89 from the front of the machine. This means includes a horizontal rock shaft 116 extending fore and aft above the roll-over unit. Said shaft is mounted in bearings supported by an L-shaped bracket 117 supported upon the bearing box 6. Centrally fixed to the rear end of shaft 116 is a cross bar 118 similar to the valve handle 102 and having its ends operatively connected to 15 the ends of the handle by pull cords 119. A similar cross bar 120 is centrally fixed to the opposite end of the rock shaft and has two pull cords 121 depending from its ends and provided with handles 122 within the reach 20 of an operator. The cross arm 120 is normally held horizontal by a tension spring 123 which is anchored to a centrally depending lug formed upon the cross arm and to a depending ear 124 carried by the bracket 117.
- 25 Mounted upon one side of the large cylinder 9 is a valve 125 for controlling the squeezing and pattern-drawn operations of the roll-over unit. This valve is substantially a duplicate of valve 89 and a detail showing and description of it is thought to be unnecessary. A pipe 126 leads from the valve to the lower end of the stem 52 and the passage 63 therein. Another pipe 127 leads from the valve to the port 66 at the upper end of the plunger 44.
- 30 Pipe 127 is formed in telescoping sections to permit movement of the plunger and is suitably packed to prevent leakage. The valve has an operating handle 128.
- 35 Fluid, preferably air under pressure, is supplied to the jolt valve 30 and the squeeze and draw valve 125 through the hollow trunnion 11. A main supply pipe 129 is connected to the nipple 19 of the plunger by a suitable stuffing box structure 130, and a passage 131 formed in cylinder 9 leads obliquely outward. A pipe 132 connects said port to valve 125, and a branch pipe 133 connects pipe 132 to the jolt valve 30. Pipe 107 which supplies the valve 89 for the roll-over and roll-back operations, leads from the supply pipe 129.
- 40 The machine is operated as follows: Valve 125 is manually operated to admit air which is supplied through the trunnion, into pipe 127 and thence to port 66 and the uppermost chamber 60 of the plunger. This operation of the valve also vents the plunger chambers 61 and 62 to atmosphere through ports 64 and 65, passage 63, pipe 126 and the exhaust port of the valve. Consequently the air admitted into chamber 60 elevates the plunger and increases the clearance between the squeeze head 45 and the flask-supporting table 23. Lock 67 automatically limits the upward movement of the plunger. The squeeze head is swung laterally out of register with the table and a flask F is placed upon a pattern plate P which is supported by the table 23 and secured thereto as indicated at 134. The pattern plate carries a pattern P' projecting upward into the flask. In order to hold the flask true upon the pattern plate the plate is provided with the usual retaining pins 135 which project through apertured ears 136 formed upon opposite sides of the flask. Having positioned the flask it is charged with sand and the jolting operation is performed by pressing the lever 32 inward. This retracts the bolt 35 and opens the valve 30 for the admission of compressed air to the lower end of the jolt cylinder through ports 25 and 27. Thereby the jolt piston is raised until it opens the exhaust port 29 whereupon it drops for jolting the sand. When this has been repeated sufficiently the lever is released, whereupon the valve 30 is automatically closed and the bolt 35 is automatically projected inward by the contraction of spring 34 for locking the jolt piston.
- 45 A squeeze board or bottom board B is next placed upon the sand in the flask; squeeze head 45 is swung back into register with the flask, and valve 125 is operated for the mold-squeezing operation. Through said valve compressed air, supplied through the trunnion, is admitted to pipe 126 and thence through stem passage 63 and ports 64 and 65 to plunger chambers 61 and 62. Here said air operates upon pistons 50 and 48 to force the plunger downward and press the squeeze head 45 against the presser board B to squeeze the mold. It will be understood that the valve 125 in its mold-squeezing adjustment vents the chamber 60 to atmosphere. The pressure developed in chambers 61 and 62 exerted upon the cooperating pistons 48 and 50 causes an effective squeezing. By the provision of tandem expansion chambers and pistons, as shown, the piston and cylinder diameters are greatly reduced and the mechanism is given an elongated form suitable for supporting the jolting mechanism and the squeeze head in spaced relation and for carrying the trunnion 11.
- 50 While holding the parts in squeezing position the valve 89 is operated for the roll-over by pulling the appropriate handle 122 at the front of the machine. The valve admits compressed air to the upper end of cylinder 82 and exhausts it from the lower end thereof.
- 55
- 60
- 65

to cause the roll-over of the mold-forming unit 2 and the inversion of the flask. During the roll-over the flask and mold are held clamped in position by the squeezing mechanism and, at the conclusion of the roll-over the weight of the flask and mold rests upon the squeeze head which then serves as a flask support.

While maintaining the rolled over position 10 of the unit 2 and the flask the valve 125 is operated for causing the pattern-drawing operation. Air is thereby exhausted from the plunger chambers 61 and 62 through the ports 64 and 65, passage 63, pipe 126 and the 15 valve exhaust port. Thereby the plunger 44 and the squeeze head 45, with the supported flask and mold, are permitted to gravitate away from the table 23. Since the table carries the pattern P' the latter is withdrawn 20 from the mold by the recession of the squeeze head. In rolled over position the hook 67 lies in an inoperative position upon the plunger head 46 to permit the greater movement of the plunger for pattern drawing. The 25 flask is next removed from the inverted squeeze head, and the valve 89 is operated from the front of the machine by the appropriate handle 122 to cause the roll-back movement of the mold-forming unit. The 30 valve does this by exhausting air from the upper end of cylinder 82 and admitting compressed air to the lower end of the cylinder.

The mold-forming unit is designed and supported for substantially balanced rotation 35 so that little power is required for the roll-over and roll-back movements. These movements are cushioned by the restricted exhaust of air from the cylinder 82 through the bleed ports 110 in the check valves 109.

It is obvious that the volumes of the plunger and cylinder spaces between pistons 50 and 59 and between piston 48 and the lower end of cylinder 9 will vary in the reciprocation of the plunger. Consequently 40 said spaces must be vented. The lower space, with reference to Fig. 2, is vented directly to atmosphere through ports 136 in the closed end 10 of the cylinder, and the upper space is vented through ports 137 in the plunger 45 which open into longitudinal grooves 138 formed in the inner walls of the cylinder and lead into said lower space. The plunger is held against turning in the cylinder by a set screw 139 threaded through the cylinder 45 and engaging in a longitudinal slot 140 formed in the outer wall of the plunger.

What we claim is:

1. A molding machine comprising a roll-over unit including a flask support mounted 50 for shifting to jolt the sand in a supported flask, fluid pressure operated means to shift said support for jolting, locking means to hold said support against shifting, manually operable means operatively connected to said 55 locking means and said fluid pressure oper-

ated means to release the locking means and cause the jolting operation, and means to automatically apply the locking means after the jolting operation; and a mounting for said unit supporting it for rotation to roll 70 over the flask.

2. A molding machine comprising a mold-forming roll-over unit including a pair of opposed flask supports spaced apart to accommodate a flask between them and permit it to rest upon one of said supports, fluid pressure operated jolt mechanism to vertically shift the latter support for jolting the sand in the mold, locking means to prevent said vertical shifting of said support, control means for the jolt mechanism, manually operable means operatively connected to said locking means and to said jolt control means for releasing the locking means and causing the jolting operation, means to automatically apply said locking means at the conclusion of the jolting operation, pattern-holding means carried by said latter flask support, and means to move one support toward the other to squeeze the interposed mold in the flask and hold the flask during the roll over; and a mounting for said unit supporting it for rotation to roll over the flask and transfer its weight from one support to the other, one support being shiftable away from the other for drawing the pattern and said locking means preventing dropping of the jolt-operated support when the pattern drawing occurs.

3. A molding machine comprising a pair 100 of opposed flask supports; a fluid pressure operated mold-squeezing and pattern-drawing mechanism connecting said supports and supporting them in spaced relation in a unit; a trunnion carried by said mechanism and extending laterally from it; and a mounting for said trunnion supporting said unit for rolling over to invert the flask and transfer it from one support to the other.

4. A roll-over molding machine comprising a pair of opposed flask supports; a fluid pressure operated mechanism supporting said flask supports in spaced relation in a unit, said mechanism being operable for shifting one flask support toward the other 110 support for mold squeezing; and a mounting for said fluid pressure operated mechanism supporting the unit through the medium of said mechanism for rotation about a lateral axis to roll over and invert the flask 115 and transfer its weight from one support to the other.

5. A molding machine comprising a pair 125 of flask supports; a roll-over unit comprising a telescoping fluid pressure operated mechanism supporting said flask supports laterally offset therefrom in opposed spaced relation to receive a mold flask therebetween, said mechanism being operable by fluid pressure to longitudinally contract it and move 130

one of said supports toward the other to squeeze a mold in an interposed flask and being operable to longitudinally extend it to move one of said supports away from the other for pattern-drawing; and a mounting for said mechanism supporting the unit through the medium of said mechanism for rotation about a lateral axis to roll over the flask and transfer the weight of the flask from one of said supports to the other.

6. A molding machine comprising a pair of flask supports; a roll-over unit comprising a fluid pressure operated mechanism supporting said flask supports laterally offset therefrom in opposed spaced relation to receive a mold flask therebetween and comprising means forming a plurality of fluid pressure chambers in tandem relation and each having a shiftable wall operatively connected to one of the flask supports, said walls being shiftable in unison in the same direction by fluid pressure applied in said chambers to the same side of each wall to move said operatively connected flask support toward the other support for mold squeezing and shiftable in the opposite direction to move one of said supports away from the other for pattern-drawing; and a mounting for said mechanism supporting the unit through the medium of said mechanism for rotation about a lateral axis to roll over the flask and transfer the weight of the flask from one of said supports to the other.

7. A molding machine comprising a roll-over unit including a pair of opposed flask supports spaced apart to accommodate a flask between them, mechanism to shift one of said supports toward and from the other for squeezing and releasing the mold, and gravity operated locking means to limit the movement of said shiftable support away from the other support; and a mounting for said unit supporting it for rotation to roll over the flask, said locking means being releasable by gravity when the unit is rolled over to permit greater movement of the shiftable support away from the other support for pattern drawing.

In testimony whereof we hereunto affix our signatures this 15th day of November, 1930.

WILLIAM H. NICHOLLS.
ARTHUR D. ZIEBARTH.
